US00D657414S

(12) United States Design Patent (10) Patent No.: US D657,414 S
Liu et al. (45) Date of Patent: * Apr. 10, 2012

(54) WRITING PAPER

(75) Inventors: Jen-Rong Liu, Kaohsiung (TW);
Shu-Wei Ho, Kaohsiung (TW)

(73) Assignee: Taiwan Hopax Chemicals Mfg. Co., Ltd. (TW)

() Term: 14 Years

(21) Appl. No.: 29/389,200

(22) Filed: Apr. 7, 2011

(30) Foreign Application Priority Data

Jan. 27, 2011 (TW) 00300435

(51) LOC (9) Cl. 19-01

(52) U.S. Cl. D19/1

(58) Field of Classification Search D19/1-8,
D19/26-31, 10-11, 100; 283/36, 45, 61,
283/62, 72, 74, 75, 81, 93, 103, 105, 115,
283/117; 40/124.05-124.06, 1.5, 299.01,
40/641; 281/2, 3.1, 5, 22, 38, 41, 51; 229/92.1;
206/214, 371; 428/79, 199, 542.6; D5/57-61,
D5/99; 402/79; 434/162

See application file for complete search history.
